(57) **CLAIM**

The ornamental design for a ceiling mounted occupancy sensor, as shown and described.

DESCRIPTION

FIG. 1 shows a top perspective view of a ceiling mounted occupancy sensor.

FIG. 2 shows a bottom perspective view of the ceiling mounted occupancy sensor.

FIG. 3 shows a top plan view of the ceiling mounted occupancy sensor.

FIG. 4 shows a bottom plan view of the ceiling mounted occupancy sensor.

FIG. 5 shows a front elevation view of the ceiling mounted occupancy sensor; and,

FIG. 6 shows a right elevation view of the ceiling mounted occupancy sensor.
